UNITED STATES PATENT OFFICE.

LUCY STOWE BIGELOW, OF KANSAS CITY, MISSOURI.

TOY VALISE.

Application filed February 25, 1926. Serial No. 90,460.

My invention relates to improvements in toy valises.

One of the objects of my invention is to provide a novel toy valise which is interiorly 5 equipped to represent, in miniature, the interior of a room, such as the interior of a sleeping car or that of a breakfast or other room.

A further object of my invention is to 10 provide a valise of the kind described, which is simple, cheap to make, relatively durable and substantial, and which will be attractive and amusing for children.

A further object of my invention is in the 15 provision of novel structural features as hereinafter set forth.

The novel features of my invention are 20 hereinafter fully described and claimed.

In the accompanying drawings which 25 illustrate the preferred embodiment of my invention,

Fig. 1 is a perspective view of my improved toy valise equipped interiorly to represent the interior of a sleeping car or a 30 breakfast room, and having the side opening closed.

Fig. 2 is an enlarged cross section on the line 2—2 of Fig. 1.

Fig. 3 is an enlarged cross section on the 35 line 3—3 of Fig. 1.

Fig. 4 is a cross section of one of the car seats, on the line 4—4 of Fig. 2.

Fig. 5 is an enlarged fragmental end elevation of the valise, showing the lid disposed 40 under the body to form a floor.

Fig. 6 is an enlarged perspective view of the valise, showing the interior, with the lid supporting the body.

Fig. 7 is a horizontal section, partly 45 broken away and the parts removed, of the device, as shown in Fig. 6.

Similar reference characters designate 50 similar parts in the different views.

My toy valise has a rectangular body 1 having one side provided with a large opening 2 through which the interior of the valise may be seen and access had thereto.

The body 1 at opposite sides of the opening 2 has two vertical guides or grooves 3 respectively, which may be formed between the body 1 and an interior lining 4, which may be card board or other suitable material. In the guides 3 is removably fitted a lid 5, having at its upper end a flange 6 adapted 55 to rest on the top of the body 1.

As shown in the drawings, the interior of

the valise has equipment means arranged to represent, in miniature, the interior of a portion of a sleeping car, 7 designating a section having the usual end walls to which are respectively attached, in any suitable manner, as by gluing to the lining 4, the backs of two seats 8, which face each other in the usual manner.

In the side of the valise opposite the side 60 having the opening are two windows 9, which are disposed between the seats, and may be respectively provided with curtains 10. Over the seats is a folding upper berth 11 which is fastened by hinges 12 to the side 65 wall having the windows 9. The berth 11 is adapted to be swung from the closed position shown in Fig. 2 and Fig. 6, to a position resting on two brackets 13, which are fastened respectively to the end walls of the 70 section 7, which is the position for use. For holding the berth 11 closed, a turn button 14 is pivoted to the ceiling of the section 7, and is adapted to engage the under side of a longitudinal flange 15 at the outer edge of 75 the berth 11.

Intermediate of the seats 8 is removably fixed a table 16 the inner end of the top of which has a downwardly extending lip 17 which is adapted to be inserted behind a 80 horizontal band 18 attached at its ends to the lining 4 of the side wall of the section 7.

The table 16 has a leg 19 the lower end of which removably engages the under side 85 of a horizontal band 20 by means of a horizontal lip 21 at the lower end of the leg. The ends of the band 20 are attached to the 90 floor of the section 7.

Mounted on the side wall of the section 95 respectively over the seats 8 may be two electric lamps 22, Fig. 6.

23 designates two dolls seated on the seats 8 to represent two persons.

Each seat 8 may have its back, ends and 100 seat portions formed from a single sheet of suitable material, such as card board, Fig. 4. The seat portion 23 of each seat 8 is bent horizontally forwardly from the back of the seat, and may be provided at its forward edge with a downwardly extending 105 stiffening lip 24, the ends of said seat portion being respectively fastened, as by gluing, to the ends of the seat, the latter forming the arms and legs of the seat.

The upper end of the back of each seat is 110 provided with two forwardly and downwardly extending lips 25, which embrace the

upper edge and forward side of a back cushion 26. A seat cushion 27 rests on the seat portion 23.

At one end of the section 7 is a linen closet 27 having a doorway adapted to be closed by a door 28. The latter is retained in the closed position by the lid 5 when the latter is in the guides 3. In the closet 27 may be placed things usually held in such car closet, as a step ladder 29, linen 30, and a satchel 31.

Aside from the windows 9, the valise when closed, has the usual appearance of the usual traveling bag.

When the valise is to be used, to play with, the lid 5 is withdrawn from the guides 3 and may be disposed under and arranged to support the body 1, Fig. 5, the flange 6 being disposed against the window side of the body, and the lid extending laterally beyond the opening side of the body, so as to represent the floor of the aisle of the car, Fig. 6.

With the omission of some of the parts usually used in a sleeping car, such as the berth 11, and brackets for supporting it, the interior equipment could well represent a breakfast room and an adjoining closet.

I do not limit my invention to the structure shown and described, as many modifications, within the scope of the appended claims, may be made without departing from the spirit of my invention.

What I claim is:—

1. A toy valise having in one side an opening and in the other side a window, and having interior equipment means including two seats at opposite sides respectively of said window, and a miniature folding upper berth above said seats.

2. A toy valise having an opening in one side and in the other side a window, a lid for said opening forming one side of the valise, and equipment means in said valise including in miniature two seats at opposite sides respectively of said window, a table between said seats, and a folding upper berth

above said seats and table arranged to represent the interior of a sleeping car section.

3. A toy valise having a side opening and in the other side a window, a removable lid 50 for said opening forming one side of said valise, and interior equipment means including in miniature two seats at opposite sides respectively of said window, and a folding upper berth above said seats and window arranged to represent the interior of a sleeping car section, said lid being adapted to be disposed under and form a support for the body of said valise and to extend laterally beyond said opening so as to represent the floor of 60 the aisle of the car.

4. A toy valise having a side opening and in the opposite side a window, and having vertical guides at opposite sides respectively of said opening, a lid removably fitted in said 65 guides and forming one side of the valise and having at its upper end a flange adapted to rest on top of the body of the valise, and interior equipment means including in miniature two seats at opposite sides respectively of said window, and a folding berth over 70 said seats arranged to represent the interior of a sleeping car section, and a linen closet at one end of said section having a door arranged to be held closed by said lid when 75 the latter is in said guides, the lid being adapted to be disposed under and to support said body and to extend laterally beyond said opening to form the floor of the aisle of the car when said flange contacts with the opposite side of the body of the valise.

5. In a toy of the kind described, the combination with a side wall member and a floor member, each having an outstanding band having its ends attached thereto, of a miniature table having a top member having an end lip engaging the inner side of the wall band, and having a leg provided with a lip 85 engaging the inner side of the floor band.

In testimony whereof I have signed my name to this specification.

LUCY STOWE BIGELOW.
